UNITED STATES PATENT OFFICE.

CHARLES BENTON GILLESPIE, OF BUFORD, NORTH DAKOTA.

STRINGED MUSICAL INSTRUMENT.

No. 903,407.

Specification of Letters Patent.

Patented Dec. 8, 1908.

Application filed March 23, 1907. Serial No. 364,698.

To all whom it may concern:

Be it known that I, CHARLES BENTON GILLESPIE, a citizen of the United States, residing at Buford, in the county of Williams and 5 State of North Dakota, have invented new and useful Improvements in Stringed Musical Instruments, of which the following is a specification.

This invention relates to musical instruments and it has particular reference to that 10 class of musical instruments in which the sound is produced by the vibration of strings that are set in motion either by means of a bow, as in a violin, or by picking with the 15 fingers, as in a guitar, a banjo, or a mandolin.

The invention has for its object to increase 20 the volume and to improve the quality of the sound; and with these and other ends in view which will readily appear as the nature of the invention is better understood, the same consists in the improved construction and novel arrangement and combination of parts which will be hereinafter fully described and particularly pointed out in the claims.

25 In the accompanying drawing has been illustrated a simple and preferred form of the invention; it being, however, understood that no limitation is necessarily made to the precise structural details therein exhibited, but 30 that changes, alterations and modifications within the scope of the invention may be resorted to when desired.

In the drawing, Figure 1 is a top plan view 35 of a musical instrument constructed in accordance with the principles of the invention. Fig. 2 is a side elevation of the same. Fig. 3 is a transverse sectional detail view, enlarged, taken on the plane indicated by the line 3—3 in Fig. 2. Fig. 4 is a longitudinal 40 sectional detail view taken on the plane indicated by the line 4—4 in Fig. 3. Fig. 5 is a transverse sectional detail view, illustrating a modification. Fig. 6 is a transverse 45 sectional detail view, illustrating a further modification.

Corresponding parts in the several figures are denoted by like characters of reference.

The invention consists essentially in combining with the neck, finger board, tail piece 50 and bridge of an ordinary stringed instrument, such as a violin, a banjo, or a guitar, a sounding box, such as that used in connection with an ordinary phonograph, containing sound producing diaphragms, and horns 55 for the purpose of increasing the volume of the sound; it being understood that within

the scope of the invention the sound producing box may be combined with the members of any of the well known stringed instruments.

For purposes of illustration I have elected in the accompanying drawings to show the head 1, finger board 2, body 3, bridge 4 and strings 5 of an ordinary violin. The body 3, the sides of which are reinforced by means of plates 6 is recessed to accommodate an ordinary phonograph sounding box 7 which is preferably of a type generally known as "duplex" containing the diaphragms 8—8 which are held in position by means of gaskets 9. 60 Horns 10—10 are connected in the usual manner with the sides of the sounding box, adjacent to the diaphragms, said horns being preferably so disposed as to diverge in a rearward direction; said horns are also preferably connected by means of a cross-bar or brace 11 with which the rear end of the body 3, which is equipped with a chin rest 12, is 65 suitably connected. The diaphragms 8 are connected by means of fastening members 70 such as screws 13 with a transmission bar, in this case consisting of an inverted T-bar 14, the head of which is engaged by the screws and the shank of which projects through an aperture in the wall or body of the sounding 75 box and carries at its upper end a cross bar 15 upon which the bridge 4 is supported; the shank of the T-bar 14 is steadied by means of holding members such as screws 16 adjusted in lugs 17 upon the sounding box and 80 provided with jam nuts 18 whereby they may be securely maintained at the proper adjustment.

Under the modification illustrated in Fig. 5, the screws 16, lugs 17 and jam nuts 18 are 85 dispensed with, and the cross-bar 15 of the T-bar 14 is provided with a V-shaped notch 19 engaging a knife edged lug 20 formed upon the wall of the sounding box.

Under the further modification illustrated 90 in Fig. 6 of the drawings, the diaphragms 8—8 are suitably connected with independent transmission bars 21—21 extending through apertures in the wall of the sounding box and provided with terminal brackets 22, the 95 undersides of which are provided with V-shaped notches 23 engaging knife edged lugs 24 upon the wall of the sounding box; said brackets 22 are provided on their upper sides with knife edged lugs 25 upon which a bridge 100 here designated 26 may be directly supported; this form of the invention is considered par-

ticularly applicable to instruments wherein a bridge of larger dimensions than that of an ordinary violin is used, such as, for instance, the bridge of a guitar.

5 The strings are applied, and placed under tension in the well known manner which is common to any of the various stringed instruments. When the strings are vibrated, the vibrations are transmitted through the 10 transmission bar or bars 14 or 21, as the case may be, to the diaphragms 8, and the sound waves are discharged through the horns with very pleasing and satisfactory results.

Having thus fully described the invention, 15 what I claim is:—

1. A musical instrument including a sounding box having a diaphragm, a transmission bar connected with the diaphragm and extending through the wall of the sounding box, 20 lugs upon the latter, holding members adjustable in the lugs and engaging the transmission bar, a bridge supported upon the transmission bar, and strings supported by the bridge.

2. A musical instrument including a duplex sounding box having a pair of diaphragms a transmission bar extending

through the wall of the sounding box and connected with the diaphragms, a pair of horns connected with the sounding box, a bridge supported upon the transmission bar, 30 and a plurality of strings under tension, said strings being supported intermediate the ends thereof by the bridge.

3. A musical instrument, comprising a neck, a finger board and a body, a duplex sounding box connected with the body and having a pair of diaphragms, a pair of horns connected with and diverging rearwardly from the sounding box, a brace connecting the horns, a transmission bar connected with the 35 diaphragms and extending through the wall of the sounding box, a bridge supported upon the transmission bar, and a plurality of strings under tension, said strings being supported intermediate their ends upon the 40 bridge.

In testimony whereof, I affix my signature in presence of two witnesses.

CHARLES BENTON GILLESPIE
